UNITED STATES PATENT OFFICE

CHRISTIAN H. T. HAGELSTEIN, OF STOUGHTON, MASSACHUSETTS, ASSIGNOR TO REECE
BUTTONHOLE MACHINE COMPANY, OF BOSTON, MASSACHUSETTS, A CORPORATION
OF MAINE

SEWING MACHINE

Application filed May 18, 1928. Serial No. 278,664.

This invention relates to sewing machines and has for its object to provide certain improvements in sewing machines all as will be more fully hereinafter set forth.

5 In order to give an understanding of the invention, I have illustrated in the drawings a selected embodiment thereof which will now be described, after which the novel features will be pointed out in the appended 10 claims.

In the drawings:

Fig. 1 is a side view of the sewing machine embodying my invention.

Fig. 2 is a section on the line 2—2 of Fig. 1.

15 Fig. 3 is a fragmentary perspective view illustrating the latch for holding the clutch controlling rod in operative position.

Fig. 4 is a section on the line 4—4 of Fig. 1.

The sewing machine herein illustrated is 20 the type commonly referred to as a "tacker," this being a sewing machine adapted to sew reinforcing seams at the ends of buttonholes or at the ends of pockets or other openings. The invention, however, is applicable to other 25 types of sewing machines and is not limited in its use to any particular type of machine.

The machine herein illustrated comprises the main frame 1 having the usual overhanging arm 2 in which is mounted the needle bar 30 3 carrying the upper needle 4.

This main frame is pivotally mounted at 5 upon a base frame 6 which is adapted to be supported on the bench or table 7 all as usual in sewing machines of this type. One purpose of pivotally mounting the main frame 1 on the base frame is to permit the main frame to be swung upwardly and backwardly about its pivot, thereby to expose the operative parts 35 beneath the bed 8 of said frame.

40 One feature of my present invention relates to certain improvements by which the main frame can be tipped up into an upright position without requiring any preliminary disconnection of the actuating parts for the 45 clutch.

The needle 4 is actuated as usual from a shaft 9 journaled in the main frame and this shaft in turn is driven from the driving shaft 10 through the medium of spiral gears 11.

50 The driving shaft 10 is driven from a driving

pulley 12 through the medium of a suitable clutch which is not shown, but is enclosed in the housing 13 carried by the shaft 10. The clutch is controlled by a clutch cone 14 slidably mounted on the shaft 10, the construction being such that when the cone is moved to the right, Fig. 2, the clutch will be engaged, while when the cone moves to the left, the clutch will be released. This cone is actuated through the medium of a clutch controlling rod 15 that is slidably mounted in the main frame and is provided with a forked arm 16, the fork of which engages in a groove 17 in the clutch controlling cone 14.

55 This clutch controlling rod 15 is normally held in its inoperative position by means of a spring 18 that normally holds it in the dotted line position, Fig. 2, in which position the clutch is released. The clutch controlling rod 15 is moved to the right or into the full 60 line position, Fig. 2, to throw the clutch into engagement by means of an actuating lever 19 which is pivoted at 20 on the main frame 1 and the upper end 21 of which engages the end of the rod 15. The lower end of the lever 19 is formed with a cam surface 22 adapted to be engaged by a roll 23 on the end of a lever 24 pivoted at 25 on the base frame 6. Said lever 24 has a link 27 connected thereto which 65 leads to a treadle or other manually operated 70 element.

75 When the clutch is disengaged, the actuating lever 19 and the clutch controlling rod 15 will be in dotted line positions, Fig. 2. To throw the clutch into engagement, the treadle or other manually operated element is actuated to pull the link 27 downwardly and thereby swing the lever 24 from the full to the dotted line position. During this swinging movement of the lever, the roll 23 engages the 80 cam face 22 and swings the actuating lever 19 from the dotted to the full line position, thereby shifting the rod 15 to the right and into the position shown in Fig. 2, which 85 movement throws the clutch into engagement, as above described.

A latch is provided for automatically engaging the rod 15 when it is in its operative position, thereby to hold the clutch in engagement until the sewing operation has been com- 130

pleted. This latch is shown at 28 and is pivotally mounted on a supporting rod 29 that is carried by the frame, said latch being adapted to drop into a recess 30 formed in the rod 15 when the rod is carried into its operative position.

The construction above described for actuating the clutch controlling rod 15 is such as to permit the main frame 1 to be swung about its pivot 5 without the necessity of disconnecting the actuating connections by which the clutch is controlled. When the main frame is lifted about its pivot, as shown by the dotted lines in Figs. 1 and 2, the cam surface 22 is merely carried away from the roll 23, and when the main frame is again brought back into its operative position, said cam surface will be automatically replaced in its operative position relative to the roll 23. This operation is due to the fact that the levers 19 and 24 are not mechanically connected together but merely have an operative engagement. The advantage of this construction is that no preliminary operation of disconnecting the treadle from the clutch actuating mechanism is required prior to swinging the main frame 1 upwardly and backwardly.

At the end of each sewing operation the latch 28 is automatically released from the notch or recess 30 and the clutch controlling rod 15 is returned to its normal or dotted line position by the spring 18, thus disengaging the clutch. The shaft 9 has a disk 31 mounted thereon provided with a projection 32 adapted to engage the nose 33 at the upper end of a vertically sliding rod 34, the latter being mounted for sliding movement in bearings 35 and 36 rigid with the main frame. The lower end of the rod 34 has a toe or lateral projection 37 extending therefrom, said projection underlying a horizontal arm 38 that is rigid with the latch 28.

The disk 31 is secured to and is rotated by the cam 47 which controls the jogging movements of the work clamp, and which makes one rotation for each sewing operation as usual in sewing machines of this type, and hence said disk will rotate once for each sewing operation. The parts are so timed that at the completion of the sewing operation the projection 32 will engage the nose 33 and thereby lift the rod 34, this lifting movement causing the toe 37 to engage the arm 38 and rock the latch 28 backwardly to release it from the recess 30.

The rod 34 is acted on by a spring 39 which normally holds it in its lowered position, said spring encircling the rod and being confined between the bearing 35 and a collar 40 which is fast on the rod. This collar carries a positioning pin 41 which extends through an opening in the bearing 36. One purpose of this positioning pin is to prevent the rod 34 from turning about its axis and thereby insuring that the nose 33 will always be main-

tained in proper position to be engaged by the projection 32.

This positioning pin 41 extends below the bearing 36 and is slotted at its lower end as shown at 42, the slotted end receiving a pin 43 which extends laterally from the arm 38. The pin is provided with an axial spring-receiving recess in which is received a spring 44 that bears against the pin 43. This spring maintains the latch yieldingly in contact with the rod 15 so that when the rod is shifted into the operative position shown in Fig. 2, the latch will automatically drop into the recess 30. The spring 44 is a relatively light spring of just sufficient strength to cause the latch 28 to function properly and this spring maintains a constant spring pressure on the latch even when the collar 40 is seated against the bearing 36.

I have shown the disk 31 as adjustably secured to the cam 47 so as to provide circumferential adjustment of the projection 32. This is provided for by making the disk 31 with slots 45 which receive clamping bolts 46 that clamp the disk to said cam member 47.

The work *w* is clamped in position between upper and lower clamping members 48 and 49. The lower clamping members 49 are formed on the ends of arms 50 and the upper clamping members 48 are formed on the ends of arms 51, all as usual in sewing machines of this type.

In order to maintain each upper arm 51 in correct alignment with its lower arm 50, I have formed each upper arm with two depending fingers 52 which embrace the lower arm, as shown in Figs. 1 and 4. These fingers permit the clamping members to move toward and from each other for clamping and unclamping the work but maintain them always in their proper position one above the other.

Having thus described the invention, what is claimed as new, and desired to be secured by Letters Patent, is:

1. In a sewing machine, the combination with a main frame carrying stitch forming mechanism of a clutch controlling rod on said main frame by which the operation of the stitch forming mechanism is controlled, an actuating lever pivoted to the main frame for operating said rod, said lever having a cam surface, a base frame on which the main frame is pivotally mounted, a manually operated lever carried by the base frame and adapted to engage said cam surface for operating the actuating lever.

2. In a sewing machine, the combination with a frame carrying stitch forming mechanism of a clutch controlling rod slidably mounted in said frame for controlling the operation of the stitch forming mechanism, said rod having a recess, a pivoted latch having an arm rigid therewith, a latch releasing rod having a toe to engage said arm, said

main frame having bearings in which the rod is slidably mounted, means to actuate the rod upon the completion of the sewing operation, a positioning pin rigid with the rod and 5 slidable on one of the bearings for holding it in operative position, and a spring carried by said positioning pin and engaging said arm thereby to yieldingly hold the latch in operative engagement with the clutch releasing 10 rod.

In testimony whereof, I have signed my name to this specification.

CHRISTIAN H. T. HAGELSTEIN.
